Delos S. Haynes,
Attorney.

UNITED STATES PATENT OFFICE

ANTONINO ZINNA, OF ST. LOUIS, MISSOURI

STERILIZER

Application filed July 13, 1928. Serial No. 292,438.

This invention relates to sterilizers and with regard to certain marked specific features to dispensing sterilizers for barbers', doctors' or vendors' instruments, absorbent 5 roll neck straps, pads, roll bandages and the like.

Among the several objects of the invention may be noted the provision of a sterilizer which carries an evaporating sterilizing fluid 10 for providing an ambient atmosphere of sterilizing vapors, there being in said ambient atmosphere a magazine type of delivery mechanism for providing successive rolls of absorbent neck straps, bandages, pads or the like; 15 the provision of means of the class described having an improved construction for effecting delivery and reloading and the provision of a device of the class described which is simple in operation and compact in construction. 20 Other objects will be in part obvious and in part pointed out hereinafter.

The invention accordingly comprises the elements and combinations of elements, features of construction and arrangements of 25 parts which will be exemplified in the structure hereinafter described, and the scope of the application of which will be indicated in the following claims.

In the accompanying drawings, in which is 30 illustrated one of various possible embodiments of the invention.

Fig. 1 is a front elevation of the sterilizer, certain portions being broken away;

Fig. 2 is a cross-section taken on line 2—2 35 of Fig. 1 showing delivery position of the device; and,

Fig. 3 is a fragmentary view of a portion of Fig. 2 showing a reloading position of the device.

40 Similar reference characters indicate corresponding parts throughout the several views of the drawings.

Referring now more particularly to Fig. 1, there is illustrated at numeral 1 a case having 45 a left-hand compartment 3 and a right-hand

compartment 5, the former carrying supporting shelves 7, having reticulations or openings 9 therein. The purpose of the shelves 7 is to support instruments such as brushes, shears, manicuring equipment and the like in 50 the case where the device is used in barber shops, and needles, scalpels and other medical instruments in the case where the device is used in a doctor's office.

On the bottom of the compartment 3 is 55 carried an open vessel 11 in which is contained an evaporating sterilizing fluid, such as formaldehyde, the purpose of which is to evaporate vapors which are adapted to pass up through the reticulations 9 to form an 60 ambient atmosphere about the instruments in compartment 3.

In order to deliver the sterilizing vapors into the right-hand compartment 5, the wall 13 dividing the compartments 3 and 5 is provided with upwardly located reticulations or openings 15, so that circulation of the vapors is effected as shown by the directional vectors in Fig. 1. The circulation is caused by means to be made clear hereinafter.

70 Removably fitted into the right-hand compartment 5 is a circular housing 17, standing on legs 19, said housing 17 having a stationary shaft 21 therein upon which is rotatably mounted a magazine 23 having a plurality of 75 peripheral recesses 25. Fastened to and rotatable with the magazine 23 is a ratchet wheel 27 adapted to be engaged by pawl 29 pivotally located on a lever 31, the latter also being rotatable on the stationary shaft and 80 extending forwardly through an opening 33 of a hinged door 35. A spring 37 reacting between a flange 39 affixed to said shaft 21 and the lever 31 tends normally to return the lever to an upward position against the top 85 of a slot 41 formed in the casing 17 and through which slot 41 the lever 31 passes.

85 The number of teeth on ratchet 27 and the number of compartments 25 in the magazine 23 are the same or they are multiples so that 90

upon depressing the lever 31 to or near the bottom of the slot 41, the magazine is advanced by an angle corresponding to the width of one chamber 25. The parts are so arranged that for each advance, one compartment is made to register with an opening 43 for delivery or loading purposes of the contents of the said respective compartment. The door 35 is cut away at 45 to permit the passage of the contents of said recesses or compartments or chambers 25.

When the door is open (and there is enough clearance of the slot 33 to permit opening), the housing 17 may be readily removed as a unit, inasmuch as it merely stands in the compartment 5 and is not bolted in. However, the housing need not be removed for reloading purposes, because there is provided, as illustrated in Figs. 2 and 3, a chute 47 which is hinged at the lower end of the cutaway opening 45, which chute in its Fig. 2 open position catches articles as they are delivered from the chambers 25 and functions as an article drop, and which in its Fig. 3 folded position is adapted to function as a reloading guide for refilling purposes.

It will be noted that the opening 45 permits the outward passage of some of the sterilizing vapor which is forced over into the chamber 5 from the chamber 3 because of its own vapor pressure. Hence proper circulation of the ambient sterilizing vapor is permitted so that it surrounds both the instruments in the compartment 3 and the articles in the magazine 23. It should be noted that the housing 17 is made up of stamped sheet metal parts which are not put together in gas-tight fashion, so that leakage at the joints permits the desirable entry of sterilizing vapor into the housing 17.

A depressing key 49 is used at the end of the lever 31 for purposes of manual operation by the finger of an operator. A sight hole 51 is provided in the door 35 for permitting examination of the successive recesses 25 as they approach their delivery positions for purposes of ascertaining their loaded or unloaded conditions, as the case may be.

The preferred application of this device is in barber shops where the formaldehyde or similar sterilization method is effective. In such an application the articles adapted to be placed in the recesses 25 comprise previously rolled absorbent neck bands. These are placed in the palm of the hand which is put into the Fig. 3 position, so that the units of rolled material are guided by the folded back chute 47 into the successive recesses 25, the key 49 being depressed intermittently for advancing successive recesses. When the first article loaded appears at the opening 51, the operator is warned that the device is about full.

To effect delivery of the devices from the magazine 23, the chute 47 is folded down and

the same operation is effected on the key 49 as was the case during the loading operation. One depression effects delivery of one band. When the last article adapted to be delivered appears at the opening 51, the operator is warned that the device is about empty. 70

It will be seen from the above that the operation of loading and delivering is greatly simplified by making the same opening function for loading devices into the magazine and for delivering them therefrom. The same kind of manipulation is used at the key 49 for loading purposes as is used for unloading purposes. 75

Where the device is used in barber shops or by vendors of articles which should be kept sanitary, a light 51 is used at the top of the case 1 for display and advertising purposes. 80

In view of the above, it will be seen that the several objects of the invention are achieved and other advantageous results attained. 85

As many changes could be made in carrying out the above constructions without departing from the scope of the invention, it is intended that all matter contained in the above description or shown in the accompanying drawings shall be interpreted as illustrative and not in a limiting sense. 90

I claim:

1. In dispensing apparatus, a case including a compartment, a rotatable magazine in said compartment having peripheral recesses for supporting articles to be dispensed, a housing surrounding said magazine and supporting the same, the housing and contained magazine being adapted to be removed as a unit from said compartment, a single outlet in the housing for delivering and receiving articles from said recesses, the housing holding the articles in the recesses when they are not positioned at said outlet, an outlet in the case registering with said outlet in the housing adapted to pass successive articles to and from the magazine, an invertible chute hinged at one edge of said outlet and having a shape such that in one position it functions as an article drop and in another position as a reloading guide for refilling purposes, repositioning being effected by the hinge thereon. 95

2. In dispensing, sterilizing apparatus, a case including a compartment, adapted to be supplied with a sterilizing vapor, a rotatable magazine in said compartment having peripheral recesses for supporting articles to be dispensed, a housing surrounding said magazine and supporting the same, the housing and contained magazine being adapted to be removed as a unit from said compartment, a single outlet in the housing for delivering and receiving articles from said recesses, the housing holding the articles in the recesses when they are not positioned at said outlet, an outlet in the case registering with said 105

outlet in the housing adapted to pass successive articles to and from the magazine, an invertible chute hinged at one edge of said outlet and having a shape such that in one 5 position it functions as an article drop and in another position as a reloading guide for refilling purposes, repositioning being effected by the hinge thereon, said housing being so constructed that permeation of the sterilizing 10 vapor is permitted to take place therein.

In testimony whereof, I have signed my name to this specification this 11th day of July, 1928.

ANTONINO ZINNA.
